FOLDING TABLE

John W. Roberts, Birmingham, Mich.

Application March 12, 1958, Serial No. 50,000

Term of patent 7 years

(Cl. D33—14)

Fig. 1 is a front elevation of a folding table showing my new design with the table in extended position;

Fig. 2 is a side elevation of the folding table shown in Fig. 1; and

Fig. 3 is a top plan elevation of the table shown in Fig. 1.

The dominant features of my design reside in those portions shown in full lines on the drawing.

I claim:

The ornamental design for a folding table, substantially as shown and described.
